BLOCK-SIGNAL SYSTEM.

1,119,953.

Specification of Letters Patent.

Patented Dec. 8, 1914.

Application filed January 31, 1910. Serial No. 540,961.

To all whom it may concern:

Be it known that I, LAURENCE A. HAWKINS, a citizen of the United States, residing at Schenectady, county of Schenectady, 5 State of New York, have invented certain new and useful Improvements in Block-Signal Systems, of which the following is a specification.

My invention relates to block signal systems for electric roads and consists in an improvement in the arrangement of track circuits and rail connections disclosed in my prior Patent No. 929,591, dated July 27, 1909. 10 In my prior patent I disclosed a system of rail connections for electric railways employing the track rails as return conductor for the power current and having a plurality of parallel tracks in which one rail of each track was bonded throughout its 20 length, so as to be conductively continuous for all currents, and the other rail sectioned to form the signal blocks, while alternate rail sections of one track were connected at both ends to the adjacent rail sections of another track so as to form a third continuous conductor for the power current independent of the two continuous rails. 25 Thus, if a road has two tracks, three-fourths 30 of the total rail conductivity is employed for returning the power current, while if a greater number of tracks are used the proportion of total rail conductivity employed may be still greater. 35 The object of my present invention is so to arrange the track circuits that the tracks may be cross-bonded every block, and to arrange the cross-bonds in such a way that they will not interfere with the proper 40 operation of the signal circuits.

In the system of my prior patent I disclosed one arrangement in which those blocks, the sectional rails of which were connected to other blocks, have their sources of current or track transformers connected to their centers. Now if adjacent blocks of the same track having their sources of current connected to their centers have those sources relatively oppositely connected, points of zero potential will be produced approximately half way between those sources and between the continuous rail of the track to which those blocks belong and

the sectional rail of the other track. Between these points a cross-bond may be placed without affecting the operation of the system. With frequent cross-bonding, however, current may flow from one track to the other, and in order to prevent the current from one track affecting the relays of the other track, my invention in another aspect further consists in using currents of different characters for different tracks. Thus, the current supplied to the track circuits of one track may be of one phase and the currents supplied to the track circuits of the other track may be of another phase such that it will not affect the relays of the first track. My invention in this latter aspect is not limited to the track circuit arrangement of my prior patent, but is applicable to any railway, having any track circuit arrangement, in which there are a plurality of tracks, the rails of which form a plurality of return conductors for the power current, and in which frequent cross-bonding between tracks is desirable.

In the appended claims I have pointed out specifically what I consider to be the novel features of my invention, which will best be understood by reference to the accompanying drawing which shows diagrammatically a block signal system arranged in accordance with my invention.

In the drawing, A and A' represent respectively the rails of two tracks of a double track electric railway. The upper rail A and the lower rail A' are both bonded throughout in the usual manner so as to be conductively continuous for all currents. 90 Alternate sections of the sectionalized rail of each track are connected at both ends to the adjacent ends of adjacent rail sections of the other track. In this manner a third continuous conductor is formed for the return 95 of the power current independently of the continuous rails. The connections between the rail sections forming this third continuous conductor are represented at a a.

B to B⁶ inclusive represent the signals for the blocks, of which six are shown in the drawing, three for each track.

C represents a generator supplying current for the signal circuits. I have represented a two-phase generator and a three-wire transmission system, c, c', c'', the wire c

- being common to both phases. The purpose of a poly-phase transmission circuit is to furnish currents of different phases to the track circuits of the two tracks.
- 5 D, D' and D² represent transformers for supplying current to the track circuits of the track A. These transformers all have their primaries connected between the transmission wires c and c^2 . The transformers 70 10 D and D², which are connected to blocks having their sectional rails connected to sectional rails of the other track, are connected to the centers of their blocks, while the transformer D' is connected to the out-going end of its block.
- 15 E to E⁵ represent track relays. These are shown diagrammatically as of the well-known induction type each comprising a short-circuited secondary member e carrying the relay contacts, a winding e' connected to the track rails, and a second winding e^2 supplied with current independently of the track circuits from transformers F to F⁶, certain of which transformers also serve 80 20 to supply current for actuating the operating mechanisms of the signals. In the blocks having the track transformers connected to their centers, as, for instance, in the block to which the signal B belongs, two 85 25 track relays E and E₁ are employed, one at each end of the block. The purpose of the central connection of the transformer with relays at each end of the block is to place the relays nearer to the transformer which 90 30 supplies them than to other transformers which could possibly supply current to them. The relay E₁, for instance, is distant only one-half a block from transformer D, while it is distant a block and a half from 95 35 transformer D². Since the block to which signal B' belongs has one rail completely insulated from the other track circuits, the central connection of the transformer is not necessary, so that I have indicated transformer D' at one end of the block and a single relay E' at the other end. A non-inductive resistance d is placed in series with the secondary of each track transformer and similar resistances d' are in series with the track windings of the relays. 100 40 These resistances are to prevent the cores of transformers or relays from being saturated by the power current, due to an unbalancing of the power current in the rails, and 45 also have the effect, so far as the transformers are concerned, of preventing a train when short-circuiting a transformer for drawing excessive current from it. Resistances d^2 are placed in series with relay 105 50 windings e^2 so as to give to the circuits of these windings the same power factor as that of the track circuits. These windings of relays E, E₁, E', E² and E₁² are supplied from the other phase than that to which 110 55 track transformers D, D' and D² are connected. Thus the currents in the two windings of these relays are 90 degrees out of phase, thus giving maximum torque.
- The transformers D and D² each have one terminal connected to the continuous rail of the track A and the other terminal connected to alternate sections of the sectionalized rail of this track; these sections are connected together through rail sections of the other track. If these transformers are relatively oppositely connected, as is shown for their primaries, a point of zero potential will exist approximately midway between them. These points are approximately at the center of the intervening 80 60 block between the continuous rail A and the sectionalized rail A'. These two points can, therefore, be connected together by a cross-bond a' without interfering with the operation of the signal circuits. Since the presence of this bond insures the maintenance of zero potential between its ends, it is not absolutely essential that transformers D and D² should be relatively oppositely connected, but the relatively opposite connection is preferable, since, when it is used, a breaking of the bond a' can have no effect on the operation of the circuits, whereas, if transformers D and D² were similarly connected and the bond a' were broken, current from transformer D would tend to energize relay E² and current from transformer D² would tend to energize relay E₁. 85 90 95
- With the frequent cross-bonding employed, current from one track may flow 100 100 into the other track and in case of broken rails this straying current may reach a considerable amount. For instance, suppose the upper rail A' were broken between transformer D⁴ and relay E⁴; current might 105 then flow from the right-hand secondary terminal of transformer D⁴, through resistance d , cross-bond a' , upper rail A, resistance d' and winding e' of relay E², bond a , winding e' and resistance d' of relay E⁴, 110 and lower rail A' back to the left-hand terminal of transformer D⁴. The transformer would under these conditions be delivering the same amount of current to relays E² and E⁴ and if this current could affect relay E² 115 a dangerous condition might result. In order to prevent current from one track affecting the relays of the other track, transformers D³, D⁴ and D⁵, which supply the track circuits of track A', are connected to 120 a different phase of the transmission circuit than that to which the transformers D, D' and D² are connected. The latter transformers are connected to wires c and c^2 , while the former are connected across wires 125 c and c' . The difference in phase between the currents impressed on the two tracks is thus 90 degrees. Now since the current in the windings e^2 of the relays of track A is ninety degrees out of phase with the track 130

currents for that track, it is in phase with the track currents of track A', so that track current from track A' straying into the track circuits of track A cannot produce any effect on the relays of track A. Similarly, the windings e^2 of the relays of track A' carry currents 90 degrees out of phase with the track currents of track A' and in phase with the track currents of track A, which latter currents cannot, therefore, affect these relays.

Many modifications may be made in the arrangement shown without departing from the spirit of my invention. For instance, in place of using resistances d^2 for obtaining the proper phase of the currents in the relay windings e^2 , any other suitable arrangement of connections may be employed for giving the desired phase difference of 90 degrees in the two windings of each relay. Furthermore, while I have selected a phase difference as the difference of character in the track currents of the two tracks for the purpose of preventing interference, it is obvious that other differences of character may be employed provided they prevent interference. Accordingly, I do not desire to limit myself to the particular connections and arrangement of parts shown and described, but aim in the appended claims to cover all modifications which are within the scope of my invention.

What I claim as new and desire to secure by Letters Patent of the United States, is,—

1. In an electric railway employing the track rails as return conductor for the power current, a plurality of parallel tracks each having one rail conductively continuous for all currents and the other sectioned to form signal blocks, bonds conductive for all currents connecting alternate rail sections of one track in series with alternate rail sections of another track thus forming a continuous conductor for power current independent of the continuous rails, and cross-bonds between tracks each extending from a point near the center of a rail section which is included in said continuous conductor to an approximately opposite point on the continuous rail of the other track.

2. In an electric railway employing the track rails as return conductor for the power current, a plurality of parallel tracks each having one rail conductively continuous for all currents and the other sectioned to form signal blocks, bonds conductive for all currents connecting alternate rail sections of one track in series with alternate rail sections of another track thus forming a continuous conductor for power current independent of the continuous rails, cross-bonds between tracks each extending from a point near the center of a rail section which is included in said continuous conductor to an approximately opposite point on the contin-

uous rail of the other track, sources of current connected to the rails of the several blocks, those blocks, the sectional rails of which are included in said continuous conductor, having their sources connected to their centers, and signal-controlling relays connected to the rails, the blocks having their sources connected to their centers having a relay at each end.

3. In an electric railway employing the track rails as return conductor for the power current, a plurality of parallel tracks each having one rail conductively continuous for all currents and the other sectioned to form signal blocks, bonds conductive for all currents connecting alternate rail sections of one track in series with alternate rail sections of another track thus forming a continuous conductor for power current independent of the continuous rails, cross-bonds between tracks each extending from a point near the center of a rail section which is included in said continuous conductor to an approximately opposite point on the continuous rail of the other track, sources of current connected to the rails of the several blocks, those blocks, the sectional rails of which are included in said continuous conductor, having their sources connected to their centers, adjacent blocks of the same track which have their sources connected to their centers having their said sources relatively oppositely connected, and signal-controlling relays connected to the rails, the blocks having their sources connected to their centers having a relay at each end.

4. In an electric railway employing the track rails as return conductor for the power current, a plurality of parallel tracks each having one rail conductively continuous for all currents and the other sectioned to form signal blocks, connections conductive for all currents between rail sections of different tracks forming with said sections a continuous conductor for power current independent of the continuous rails, signal-controlling relays connected to the track rails, and sources of alternating current for said relays connected to the track rails, the currents supplied to one track being of a different character from that supplied to another track.

5. In an electric railway employing the track rails as return conductor for the power current, a plurality of parallel tracks each having one rail conductively continuous for all currents and the other sectioned to form signal blocks, the blocks of each track being substantially oppositely located, connections conductive for all currents between both ends of alternate rail sections of one track and the adjacent ends of the intermediate sections of another track, said connections forming with said rail sections a continuous conductor for power current in-

- dependent of the continuous rails, signal-controlling relays connected to the track rails, and sources of alternating current for said relays connected to the track rails, the 5 currents supplied to one track being of a different character from that supplied to another track.
6. In an electric railway employing the track rails as return conductor for the power current, a plurality of parallel tracks having their rails connected to form a plurality of return conductors for the power current, cross-bonds cross-connecting the rails of different tracks every block, signal-controlling relays connected to the track rails, and sources of alternating current for the relays connected to the track rails, the current supplied by the sources for different tracks being of different characters.
- 20 7. In an electric railway employing the track rails as return conductor for the power current, a plurality of parallel tracks each having one rail conductively continuous for all currents and the other sectioned 25 to form signal blocks, bonds conductive for all currents connecting alternate rail sections of one track in series with alternate rail sections of another track thus forming a continuous conductor for power current in- 30 dependent of the continuous rails, cross-bonds between tracks each extending from a point near the center of a rail section which is included in said continuous conductor to an approximately opposite point 35 on the continuous rail of the other track, signal controlling relays connected to the track rails, and sources of alternating current for the relays connected to the track rails, the currents supplied by the sources 40 for different tracks being of different characters.
8. In an electric railway employing the track rails as return conductor for the power current, a plurality of parallel tracks 45 each having one rail conductively continuous for all currents and the other sectioned to form signal blocks, bonds conductive for
- all currents connecting alternate rail sections of one track in series with alternate rail sections of another track thus forming 50 a continuous conductor for power current independent of the continuous rails, cross-bonds between tracks each extending from a point near the center of a rail section which is included in said continuous conductor 55 to an approximately opposite point on the continuous rail of the other track, sources of current connected to the rails of the several blocks, those blocks, the sectional rails of which are included in said 60 continuous conductor, having their sources connected to their centers, the current supplied by the sources for different tracks being of different characters, and signal-controlling relays connected to the rails, the 65 blocks having their sources connected to their centers having a relay at each end.
9. In an electric railway the track rails of which are included in the circuit of the propulsion current, a plurality of parallel 70 tracks each having one rail conductively continuous for all currents and the other rail sectioned to form signal blocks, the blocks of each track being substantially op- 75 positely located, connections conductive for all currents between both ends of alternate rail sections of one track and the sections of another track adjacent the sections opposite said alternate sections, said connections forming with said rail sections a continuous 80 conductor for power current independent of the continuous rails and cross bonds between tracks each extending from a point near the center of a rail section which is included in said continuous conductor to an approximately 85 opposite point of the continuous rail of the other track.

In witness whereof, I have hereunto set my hand this 29th day of January, 1910.

LAURENCE A. HAWKINS.
